United States Patent Office

Des. 188,312
Patented July 5, 1960

188,312

COMBINED RAILING POST AND BRACKET

Louis Blum, Pittsburgh, Pa., assignor to Blumcraft of Pittsburgh, Pittsburgh, Pa., a firm

Filed Feb. 8, 1960, Ser. No. 59,295

Term of patent 14 years

(Cl. D13—7)

FIG. 1

FIG. 2

FIG. 3

FIG. 4

FIG. 5

Fig. 1 is a front elevational view of a combined railing post and bracket embodying my new design;

Fig. 2 is a side elevational view thereof;

Fig. 3 is a rear elevational view thereof;

Fig. 4 is a top plan view thereof; and

Fig. 5 is a bottom plan view.

The post is broken away in the center to indicate indeterminate length.

I claim:

The ornamental design for a combined railing post and bracket, as shown and described.
